UNITED STATES PATENT OFFICE.

LOUIS PAULERO, OF PETERSBURG, VIRGINIA, ASSIGNOR TO INDUSTRO-ELECTRIC TOOLS, INC., A CORPORATION OF VIRGINIA.

ELECTRIC-CURRENT-SUPPLYING DEVICE.

Application filed July 27, 1922. Serial No. 578,018.

To all whom it may concern:

Be it known that I, LOUIS PAULERO, a citizen of the United States, residing at Petersburg, in the county of Dinwiddie and State of Virginia, have invented certain new and useful Improvements in Electric-Current-Supplying Devices, of which the following is a specification.

This invention relates to improvements in electric current distributing devices for supplying electric current to translating devices such as electrically operated reciprocating hammers.

The objects of the invention are, first, to provide a novel and efficient means for supplying from a single generator electric current impulses to two hammers or other translating devices to operate them at different speeds by supplying a greater number of impulses to one hammer than to the other; second, to provide a means to prevent any material fall in voltage when additional hammers or other devices are cut into the circuits operating devices at different speeds from a common generator; and, third, to provide a novel means to prevent the leakage of current through a dead segment of a commutator of the switch device at or about the time that the supply of current to one coil of a hammer or other device is stopped and the supply of current to the other coil thereof is started.

The invention consists of the elements and the combinations of them hereinafter described and claimed.

In the accompanying drawings, illustrating the invention,

Figure 1 is a diagrammatic view showing the elements of my electric current distributing device and the electrical connections thereof.

Figure 2 is a view of the armature of the generator, its shaft and the commutating switch device thereon.

Figures 3, 4 and 5 are transverse sections of the switch device, on lines 3-3, 4-4 and 5-5 of Fig. 2, respectively.

Figure 6 is a longitudinal section through the switch device, on line 6-6 of Fig. 4.

Referring to the drawings, 2 designates the frame of the generator, 7, 8, 9 and 10 the magnetic pole pieces, 11 the armature shaft, 12 the armature, 13, 14, 15 and 16 the armature coils, 17, 18, 19 and 20 the shunt windings on the pole pieces 7, 8, 9 and 10, respec-

tively, 21 the generator commutator having the four segments 22, 23, 24 and 25, and 26 and 27 the brushes co-operating with the commutator 21. The coils 13, 14, 15 and 16 are connected to the commutator segments 22, 23, 24 and 25 by wires 28, 29, 30 and 31, and the commutator brushes 26 and 27 are connected to the field coils 17, 18, 19 and 20 of the generator by wires 32 and 33, respectively, in the usual well known manner.

For purposes of illustration in Fig. 1 I have shown four armature coils and their four corresponding segments in the commutator 21, but it will be understood that more of these coils and segments will be used in actual practice, in accordance with the type of standard machine selected.

The construction and operation of the generator, thus far described, is common and well known and no detailed description thereof is deemed necessary herein.

Mounted on the commutator shaft 11 to turn therewith are a collecting ring 34 and commutators 35 and 36 of a commutating switch device for supplying current impulses from the generator to two translating devices 37 and 38. For purposes of illustration I have shown each translating device as the two coaxial solenoid coils of an electric hammer, 39 and 40 designating the coils of the hammer 37, and 41 and 42 designating the coils of the hammer 38.

To maintain the proper voltage in the magnetizing circuits hereinafter described which operate the hammers 37 and 38 or, in other words, to prevent the voltage from dropping whenever the load is put on the generator, I provide the generator pole pieces 7, 8, 9 and 10 with series coils 43, 44, 45 and 46, through which the magnetizing current is passed after leaving the generator and before reaching the hammers 37 and 38. These series coils are so wound and connected that they supplement the shunt coils in building up the field of the generator, as will be hereinafter described.

The collecting ring 34 is a continuous ring formed of brass or other suitable current conducting material and it is mounted on an insulating bushing 47 on a sleeve 48 which is fixed on the armature shaft 11, and the ring 34 is engaged by a brush 49 which is suitably mounted on the frame of the generator.

The commutator 35 comprises two oppositely-arranged conducting or live segments 50 and 51, and two pairs of interposed non-conducting or dead segments, 52, 52 and 53, 53, arranged opposite to each other between the ends of the live segments 50 and 51. The live segments each extend around substantially ninety degrees or one-quarter of the commutator 35 and they are electrically 10 connected by a wire 54. The segments 50, 51, 52 and 53 extend around the bushing 47 and the adjacent ends thereof are slightly separated by interposed plates or pieces of insulating material 55, as clearly shown in 15 Fig. 4. The commutator 35 is engaged by two brushes 56 and 57 arranged ninety degrees apart around the commutator and suitably mounted on the frame of the generator.

The commutator 36 comprises a conducting or live segment 58 extending substantially around ninety degrees or one quarter of the commutator and two dead segments 59, 59 which with insulating plates or pieces 60 interposed between the segments 58 20 and 59 and separating them slightly complete the commutator ring. The commutator 36 is engaged by two diametrically opposite brushes 61 and 62 which are suitably mounted on the generator frame.

30 It is necessary that the live and dead segments of the two commutators 35 and 36 be formed of the same or substantially the same metal, and that the brushes co-operating therewith shall rest against the adjacent ends of two segments at the same time, as the segments succeed one another in passing the brushes, for uniform wear. Therefore, to prevent the leakage of current from one coil of a hammer to the other coil 35 thereof through a dead segment of either of the commutators 35 and 36 at or about the time that the supply of current to one coil of a hammer is stopped and the supply of current to the other coil thereof is started, 40 or at the time the two brushes of either of the commutators 35 and 36 change, one to a live segment and the other to a dead segment, I provide the commutator 36 with two dead segments 59, 59 insulated from 45 each other so that current cannot flow through them from one to the other of the brushes 61 and 62 when the brushes bridge the ends of the live segment 58 and the adjacent ends of the two dead segments 59, 59; and I provide the commutator 35 with 50 two pairs of dead segments 52, 52 and 53, 53 and insulate the segments of each pair from each other for a like purpose of preventing the flow of current through them 55 from one to the other of the two brushes 56 and 57 when they bridge the ends of a live segment and the two adjacent ends of the two pairs of dead segments.

60 The commutators 35 and 36 surround the bushing 47 and are slightly separated and

insulated from each other and from the collecting ring 34 longitudinally of the armature shaft 11 by insulating rings 63 separated by metal rings 64, as shown in Fig. 6. The collecting ring 34 and commutators 35 70 and 36 and their interposed spacing rings are clamped together by and between a collar 65 formed on one end of the sleeve 48 and a head or collar 66 screwed on to the other end of the sleeve 48, and insulated 75 from the ring 34 and commutator 36 by interposed rings 67 and 68, respectively, of insulating material.

The connections between collecting ring 34 and the commutators 35 and 36 of the 80 commutating switch device, and between them and the generator commutator 12 are as follows:

The segment 23 is connected to the collecting ring 34 by a wire 70, the segment 22 85 of the generator commutator is connected to the segment 51 of the commutator 35 by a wire 71, the segments 50 and 51 of the commutator 35 are connected to the segment 58 90 of the commutator 36 by the wire 54 and a wire 72.

The electrical connections leading from the brushes of the commutating switch device to the hammers 37 and 38 are as follows:

95 The brush 49 is connected to one end of each coil 39 and 40 of the hammer 37 by a wire 73, and to one end of each coil 41 and 42 of the hammer 38 by the wire 73 and a branch wire 74 leading therefrom. A wire 75 connects the brush 57 and one end of the series coil 43, and a wire 76 connects the other end of the series coil 43 and the end of the hammer coil 39 remote from the end thereof connected to the wire 73. A wire 77 connects the brush 56 and one end of the series coil 45, and a wire 78 connects the other end of the series coil 45 and the end of the hammer coil 40 remote from the end thereof connected to the wire 73. A wire 79 connects the brush 62 and one end of the series coil 44, and a wire 80 connects the other end of the series coil 44 and the end of the hammer coil 41 remote from the end thereof connected to the wire 74. A wire 81 connects the brush 61 and one end of the series coil 46, and a wire 82 connects the other end of the series coil 46 and the end of the hammer coil 42 remote from the end thereof connected to the wire 74.

100 During the operation of the generator the courses of the current impulses for the translating devices or hammers 37 and 38 are as follows:

105 For the hammer 37, the current flows from the armature 12 through wire 28, segment 22 of the generator commutator, wire 71, segment 51, brush 57, wire 75, series coil 43, wire 76, hammer coil 39, wire 73, brush 49, collecting ring 34, wire 70, segment 23 110

130

of the generator commutator, and back to the armature 12 through the wire 29, during one quarter revolution of the armature 12. During the next quarter revolution of the armature 12, the current flows through wire 29, segment 23 of the generator commutator, wire 70, collecting ring 34, brush 49, wire 73, hammer coil 40, wire 78, series coil 45, wire 77, brush 56, segment 50, wire 54, segment 51, wire 71, segment 22 of the generator commutator, and back to the armature 12 through wire 28. Thus the hammer coils each receive a current impulse for one half revolution of the armature. During the following one half revolution of the armature 12, the hammer coils 39 and 40 receive like impulses through the same courses, so that the hammer 37 will receive four impulses during each revolution of the armature 12.

For the hammer 38 the current flows through wire 28, segment 22 of the generator commutator, wire 71, segment 51, wire 72, segment 58, brush 62, wire 79, series coil 44, wire 80, hammer coil 41, wires 74 and 73, brush 49, collecting ring 34, wire 70, segment 23 of the generator commutator, and back to the armature 12 through wire 29, within one half revolution of the armature 12 and while the segment 58 is passing under the brush 62. Within the next half revolution of the armature 12, and while the segment 58 is passing under the brush 61, the current flows through wire 28, segment 22, wire 71, segment 51, wire 72, segment 58, brush 61, wire 81, series coil 46, wire 82, hammer coil 42, wires 74 and 73, brush 49, collecting ring 34, wire 70, segment 23 of the generator commutator, and back to the armature 12 through wire 29. Thus the hammer coils 41 and 42 each receive a current impulse during each revolution of the armature.

It will now be understood that during the operation of the generator, the coils 39 and 40 of the hammer 37 will receive impulses in alternate succession causing its plunger to reciprocate, and that the coils 41 and 42 of the hammer 38 will receive impulses in alternate succession causing its plunger to reciprocate, and that the coils of the hammer 38 receive two impulses during each revolution of the armature, and the coils of the hammer 37 receive four impulses during each revolution of the armature, causing the hammer 38 to operate at one-half the speed of the hammer 37.

The current passing through the series coils 43, 44, 45 and 46 during the operation of the hammers 37 and 38 supplements the current of the shunt coils 17, 18, 19 and 20, and serves to build up the field of the generator and prevent a fall in voltage due to the presence of the load of the hammers 37 and 38 on the generator.

The number of turns in the several series

windings of the generator may be varied, as occasion may require, to suit the particular characteristics of the translating devices in properly building up the field of the generator.

70

I claim as my invention:

1. The combination of two electrical translating devices, a generator having a plurality of pairs of pole pieces, a plurality of pairs of series windings supplementing the main field windings of the generator, means forming electric circuits including certain of said series windings therein and a commutator for supplying impulses from the generator to one of said devices, and means forming electric circuits including certain of said series windings therein and a commutator for supplying electrical impulses from the generator to the other of said devices, one of said means supplying a greater number of impulses to its series windings and its translating device per revolution of the generator armature than the other.

2. The combination of two electrical translating devices, a generator having a plurality of pairs of pole pieces, series windings corresponding in number with the pole pieces and supplementing the main field windings of the generator, means forming electric circuits including certain of said series windings therein and a commutator for supplying impulses from the generator to one of said devices, and means forming electric circuits including certain of said series windings therein and a commutator for supplying electrical impulses from the generator to the other of said devices, one of said means supplying a greater number of impulses to its series windings and its translating device per revolution of the generator armature than the other.

3. The combination of two electrical translating devices each having two magnetic coils, an electrical generator having series windings supplementing its main field windings, and a commutating switch devices carried by the armature shaft of the generator for supplying the series windings with the electrical impulses and for supplying the coils of each translating device with electrical impulses in alternate succession and comprising a collecting ring electrically connected to each translating device and to a segment of the generator commutator, a distributing commutator provided with means to electrically connect the coils of one translating device and a segment of the generator commutator, and a distributing commutator provided with means to electrically connect the coils of the other translating device and a segment of the generator commutator, one of said distributing commutators making and breaking its electrical connections with its translating de-

100

105

130

vice and certain of said series windings a greater number of times than the other per revolution of the armature shaft.

4. The combination of two electrical translating devices each having two magnetic coils, an electrical generator having series windings supplementing its main field windings, a commutating switch device carried by the armature shaft of the generator for supplying the series windings with the electrical impulses and for supplying the coils of each translating device with electrical impulses in alternate succession and comprising a collecting ring, electrically connected to a segment of the generator commutator and two distributing commutators having live segments electrically connected to a segment of the generator

commutator, one distributing commutator having more live segments than the other, 20 a brush co-operating with the collecting ring and electrically connected to the coils of each translating device, two brushes co-operating with one of the distributing commutators and electrically connected with 25 certain of the series windings and the respective coils of one translating device, and two brushes co-operating with the other distributing commutator and electrically connected with certain of the series windings and the respective coils of the other translating device. 30

In testimony whereof I affix my signature hereto.

LOUIS PAULERO.
